US0D1056337S

(12) **United States Design Patent** (10) Patent No.: **US D1,056,337 S**
(45) Date of Patent: ** Dec. 31, 2024

(54) **SHAVING COMPOSITION APPLICATOR**

(71) Applicant: **The Gillette Company LLC**, Boston, MA (US)

(72) Inventors: **Jonathan William Staudt**, Mt. Healthy, OH (US); **Jack C. Chang**, Mason, OH (US)

(73) Assignee: **The Gillette Company LLC**, Boston, MA (US)

(**) Term: **15 Years**

(21) Appl. No.: **29/847,255**

(22) Filed: **Jul. 22, 2022**

(51) LOC (14) Cl. **28-02**

(52) U.S. Cl.

USPC **D28/7**

(58) **Field of Classification Search**

(57) **CLAIM**

The ornamental design for a shaving composition applicator as shown and described.

DESCRIPTION

FIG. 1 is a front perspective view of a shaving composition applicator showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The dash lines shown illustrate portions of the shaving composition applicator and form no part of the claimed design.

1 Claim, 8 Drawing Sheets
